(57) **CLAIM**

The ornamental design for a kitchen drain strainer, as shown and described.

DESCRIPTION

FIG. 1 is a top perspective view of a kitchen drain strainer, showing my new design;

FIG. 2 is a right, bottom perspective view thereof;

FIG. 3 is a front, bottom perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is a partial enlarged view of FIG. 1;

FIG. 11 is a partial enlarged view of FIG. 2;

FIG. 12 is a partial enlarged view of FIG. 3;

FIG. 13 is a partial enlarged view of FIG. 4;

FIG. 14 is a partial enlarged view of FIG. 6; and,

FIG. 15 is a partial enlarged view of FIG. 9.

The evenly spaced broken lines along the bottom of the article depict a portion of the kitchen drain strainer that forms no part of the claimed design. The remaining broken lines denote the boundaries of the enlarged areas and form no part of the part of the claim.
